UNITED STATES PATENT OFFICE

124,074

DESIGN FOR A BOY'S CAP

Morris Greenberg and Jack Wax, Chicago, Ill.

Application September 26, 1940, Serial No. 95,384

Term of patent 3½ years

To all whom it may concern:

Be it known that we, Morris Greenberg and Jack Wax, both citizens of the United States of America, residing in the city of Chicago and county of Cook, State of Illinois, have invented a new, original, and ornamental Design for a Boy's Cap, of which the following is a specification, reference being had to the accompanying drawing, forming part thereof.

Fig. 1 is a front perspective view of a boy's cap showing our new design.

Fig. 2 is a rear perspective view thereof.

We claim:

The ornamental design for a boy's cap, as shown.

MORRIS GREENBERG.
JACK WAX.
